(57) **CLAIM**

The ornamental design for a mesh light, as shown and described.

DESCRIPTION

FIG. 1 is a perspective view of a mesh light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is an enlarged view of portion 9 shown in FIG. 2; and, FIG. 10 is an enlarged view of portion 10 shown in FIG. 2. The mesh light is shown with a symbolic break in its length and the appearance of any portion of the mesh light between the break lines form no part of the claimed design. The broken lines in the drawings depict portions of the mesh light that form no part of the claimed design. The dot-dash lines encircling enlarged views in FIGS. 2, 9, and 10 are for annotative purposes only and form no part of the claimed design.
